COIN MECHANISM FOR GAS AND ELECTRICITY METERS AND THE LIKE

Ernest William Smith and Arthur Charles,
London, EnglandApplication May 2, 1933, Serial No. 668,952
In Great Britain January 12, 1933

3 Claims. (Cl. 194—1)

This invention relates to coin freed mechanism for gas and electricity meters and like mechanisms provided with a rotatable coin holder into which the coins are inserted against

5 the action of a force resiliently applied.

In such coin holder mechanism it frequently happens that the coin is not wholly introduced into the slot but remains partially projecting therefrom and where the slot is provided in a 10 fixed plate with reference to which the coin holder has relative movement the partially projecting coin obstructs the rotation of the coin holder.

The invention has among its objects to provide 15 means automatically to ensure the insertion of the coin into the coin holder pocket to the full extent before the coin holder is rotated, to provide means whereby the coin slot in the outer fixed plate is closed before the coin holder is moved and to provide a lock between the coin holder and the fixed plate which may be automatically released when the handle of the coin holder is operated.

According to the invention the coin holder is 20 rotated relatively to the fixed plate by means of a handle adapted for relative movement in a limited degree with reference to the coin holder and the said handle carries in a position to the rear of the fixed plate a cam plate which, in 25 the rotation of the handle to rotate the coin holder, is caused to travel across the slot in the fixed plate and to apply a force in the direction of the coin holder pocket upon the edge of the coin protruding through the slot in the 30 fixed plate.

According to the invention, moreover, the coin holder is adapted to be locked to the fixed plate in a position in which the coin pocket is opposite the slot in the fixed plate by means of a 35 catch carried by the coin holder and engaging the fixed plate and so disposed that on the completion of the movement of the cam across the slot in the fixed plate the cam serves to disengage the catch from the fixed plate and 40 thus to permit the coin holder to rotate relatively to the fixed plate.

According to the invention, moreover, the cam and the handle with which it is engaged are 45 provided to be relatively movable with reference to the coin holder in such manner that when the cam has pressed the projecting coin into the slot of the fixed plate, and has also advantageously closed the slot in the fixed plate, the coin holder being freed by the catch is 50 positively rotated with reference to the fixed plate.

The invention further comprises the features of construction hereinafter described.

The invention is illustrated, by way of example, in the accompanying drawing.

Figure 1 is a plan view of a price change disc and coin holder supported thereon illustrating the coin injector mechanism according to the invention.

Figure 2 is a cross-section of the price change disc and coin holder carrier disc.

Figure 3 is a front view of the coin holder carrier disc with the associated parts.

In carrying the invention into effect according to a particular construction of coin holder mechanism adapted for use in respect of a gas 15 prepayment meter, as illustrated in the drawing, the coin holder *a* is mounted in the usual manner upon a carrier disc *b* rotatably disposed to the rear of the fixed price change disc *c*.

A clearance recess or space *b*¹ is provided 20 between the price change disc and the coin holder carrier disc, which recess may be formed either in the forward face of the carrier disc or in the rear face of the price change disc or

partly in both, and is advantageously of circular 25 form. Within the said recess there is mounted a cam plate *d* of segment-like form, which, in coincidence with the axis of the coin holder, is provided with an elongated hole *d*¹ to be received upon a short spindle *e*¹ of similar cross-

section provided upon the handle *e* of the coin 30 holder, the said spindle being introduced through the forward face of the price change disc *c* and through a suitable hole in the carrier disc *b*.

The portion of the spindle *e*¹ projecting through the carrier disc is circumferentially 35 grooved at *e*² to receive a forked spring washer *f* or clip by which the spindle is retained in its position relatively to the price change disc and the carrier disc.

The forward edge of the cam plate *d* considered in the direction of rotation of the handle *e* for turning the coin holder *a*, is so formed that in the initial position of the handle the said forward edge of the cam plate lies to the rear of the slot or slots *d*² by which coins are introduced

into the coin holder *a*, so that when the handle *e* is subjected to rotation to effect the rotation of the coin holder the forward edge of the cam plate is caused to traverse the slot while lying at an angle transversely thereto in such manner as to impart to a coin projecting from the slot pressure in the direction of the coin pocket, and

thus in the continued rotation of the handle to 40 45 50 55

the slot or slots *d*² by which coins are introduced into the coin holder *a*, so that when the handle *e* is subjected to rotation to effect the rotation of the coin holder the forward edge of the cam plate is caused to traverse the slot while lying at an angle transversely thereto in such manner as to impart to a coin projecting from the slot pressure in the direction of the coin pocket, and thus in the continued rotation of the handle to 55

pass between the price change disc and the coin and to obturate the slot.

In order that the carrier disc may be locked to the price change disc when the coin slots are in coincidence the carrier disc is provided with a catch g in the form of a leaf spring arm extending radially on the rear face and mounted at its inner end by means of a rivet or screw upon the carrier disc b and having its outer end diverted to form a catch element substantially at right angles to the plate, which element is adapted to extend through an opening b^2 in the carrier disc to enter into a slot or recess c^1 in the price change disc. The said catch is further provided with a stud, pin or projection g^1 , which may be pressed from the metal of which it is formed, which stud, pin or projection extends through the recess or hole b^2 in the carrier disc into the path of the forward edge 20 of the cam plate at a position to be engaged by the said forward edge when the cam plate has obturated the slot. By such means in the continued rotation of the cam plate relatively to the carrier disc the catch g is pressed rearwardly to disengage from the price change disc. The extent of rotation of the cam plate relatively to the carrier disc is determined by a stop b^3 mounted on the forward face of the carrier disc b or pressed out of the metal from 30 which it is formed, such stop being engaged by the forward edge of the cam plate d , after the cam plate has released the catch g , to carry the coin holder forward with the handle. It will be understood that the invention is not limited to the details of construction hereinbefore described and that it may be applied to coin holder mechanisms in which a plurality of coin slots are provided. It is only necessary in this case that the forward edge of the cam plate 40 should be formed accordingly in order that it may press inward a coin in any one of the slots. It will also be understood that the particular form of catch by which the carrier disc is locked to the price change disc may be varied 45 so long as it is of a construction to permit release by the cam plate in its rotation relatively to the carrier disc. It will further be

understood that the coin holder may be constructed in any suitable manner and the coin inserted in the coin pocket of the coin holder may be rendered effective to carry out its intended function in any suitable manner without affecting the scope of the invention. 5

We claim:

1. Coin-freed mechanism for gas and electricity meters and the like, comprising a fixed plate with coin slot, a coin holder rotatable relatively to the fixed plate and into which coins are inserted through the coin slot in the fixed plate against the action of a force resiliently applied, a handle for rotating the coin holder and a cam plate carried by the said handle to the rear of the fixed plate, which cam plate is caused to traverse the slot and to present to the periphery of a coin projecting from the slot an edge which in traversing the slot advances along the slot to press the coin completely into the coin 20 holder.

2. Coin freed mechanism according to claim 1, comprising a catch element for locking the coin holder relatively to the fixed plate in the position in which the coin holder is aligned with the coin slot, and an element such as a recess for co-operating with the said catch element, the said elements being provided respectively upon the coin holder and upon the fixed plate, the element upon the fixed plate being positioned 30 adjacent the coin slot and in the path of the cam plate in its movement after passing the slot and being so disposed that on the completion of the movement of the cam plate the cam plate disengages the catch and releases the 35 coin holder to rotate relatively to the fixed plate.

3. Coin freed mechanism according to claim 1, provided with a stop upon the coin holder, said stop being positioned in the path of the cam plate and determining the relative movement of the handle with respect to the coin holder, such that when the cam plate contacts with the stop the coin holder is rotated by the movement of the handle.
